UNITED STATES PATENT OFFICE.

FREDERICK A. HART, OF NEWARK, NEW JERSEY, ASSIGNOR TO JOHN T. UNDERWOOD,
OF BROOKLYN, NEW YORK.

VARIABLE-THROW DEVICE.

1,105,774.

Specification of Letters Patent.

Patented Aug. 4, 1914.

Original application filed December 10, 1908. Serial No. 466,836. Divided and this application filed February 6, 1912. Serial No. 675,773.

To all whom it may concern:

Be it known that I, FREDERICK A. HART, a citizen of the United States, residing at Newark, in the county of Essex and State of New Jersey, have invented certain new and useful Improvements in Variable-Throw Devices; and I do hereby declare the following to be a full, clear, and exact description of the invention, such as will enable others skilled in the art to which it appertains to make and use the same.

Broadly, my invention has for its object to provide a variable throw device, and to such end the invention consists of the novel devices and combinations of devices herein-after described and defined in the claims.

The present application is filed as a division of my prior pending application, S. N. 466,836, filed of date December 10th, 1908, title "Combined typewriting and computing machine." In the said prior application the variable throw device, which is made the subject of this application, is shown in use as an adjustable means for imparting variable return movements to the typewriter carriage; or, in other words, for bringing the typewriter carriage to different desired normal positions toward the right under the constant predetermined movements of the operating lever of the computer.

The improved variable throw device is capable of numerous different uses, but, in so far as its particular application is illustrated in the drawings, it is shown as especially designed for the above noted particular uses.

In the accompanying drawings, which illustrate the invention, like characters indicate like parts throughout the several views.

Referring to the drawings, Figure 1 is a view in left side elevation, showing the variable throw device designed as above indicated; Fig. 2 is a plan view of the parts shown in Fig. 1, some parts being broken away and some parts in section; Fig. 3 is a vertical section taken approximately on the line $x^3 x^3$ of Fig. 2, but illustrating different positions of the parts; and Fig. 4 is a horizontal view taken approximately on the line $x^4 x^4$ of Fig. 1.

Describing this variable throw device, designed for the particular uses, above stated, a flexible connection such as a tape c^{34} is attached to the free end of a typewriter line

feed, not shown, and is secured to and adapted to be wound upon a slack take-up wheel c^{37} . This wheel c^{37} is suitably mounted on the adjacent side of the frame 30 and carries a spur pinion c^{38} that meshes with a main spur gear c^{39} , loosely journaled on a shaft c^{12} , supported by the frame 30. An operating lever c^{13} is mounted on the shaft c^{12} adjacent to the main gear c^{39} , and the said two elements c^{12} and c^{39} are free for independent rotary or oscillatory movements. The operating lever c^{13} carries a spur pinion c^{40} that is in constant mesh with the main gear c^{39} and is adapted to be engaged with a similar spur pinion c^{41} which latter also meshes with the main gear c^{39} . This pinion c^{41} is loosely journaled in the outer extremity of a supporting arm c^{42} which arm, as shown, is bifurcated and straddles the main gear c^{39} , and is loosely journaled on the shaft c^{12} . Preferably, the supporting arm c^{42} engages the pinion c^{41} under friction to prevent the said arm from being accidentally moved from any set position on the gear c^{39} . However, the arm c^{42} may be easily moved so as to set the pinion c^{41} in any position desired on the gear c^{39} ; and, hence, normally any desired distance away from the pinion c^{40} of the operating lever c^{13} .

As is evident, when the operating lever c^{13} is moved forward or toward the left from its normal position, shown in Fig. 1, the main gear c^{39} , pinion c^{38} and other parts, driven therefrom, will remain stationary and the pinion c^{40} will freely rotate until the said pinion c^{40} is moved into engagement with the pinion c^{41} , whereupon the two pinions, by their opposing action or tendency to rotate the gear c^{39} , will lock the said main gear c^{39} to the operating lever c^{13} so that subsequent or continued movement of the said operating lever will positively rotate the said gear c^{39} , and parts driven therefrom. In this way, any part which receives movement from the gear c^{39} may, by a predetermined movement of the operating lever through a constant arc, be given predetermined variable movements depending on the setting of the arm c^{42} and pinion c^{40} . Otherwise stated, the nearer the said pinion c^{41} is normally set to the pinion c^{40} , the greater will be the movement which will be imparted to the main gear c^{39} and parts driven there-

from, under a complete predetermined movement of the operating lever between certain points as, for instance, between points determined by fixed stops γ and γ' .

5. It is evident that the frictional engagement between the pinion c^{41} and its supporting arm c^{42} , is not at all required or relied upon to prevent movement of the said pinion and arm in respect to the gear c^{39} at a time when the two pinions c^{40} and c^{41} are engaged; for, it is well understood that two pinions or gears engaged with each other and with a throw pinion or gear, will interlock so that no one of the three can rotate 10 in respect to the other.

15 The tape c^{34} may be spring actuated, as by the usual carriage feed tension, and will therefore operate wheel c^{37} , upon return of lever c^{13} , causing wheel c^{37} through pinions c^{38} to return the gear wheel c^{39} to normal 20 position.

25 As already stated, this variable throw device is capable of numerous uses and the particular application thereof, shown in the drawings and illustrated more fully in my said prior application, is only one of these many possible uses.

What I claim is:

30 1. A variable throw device comprising a main gear, a lever and an arm pivoted on the axis of said main gear, and pinions journaled on said lever and arm, in constant mesh with said main gear and engageable with each other to variably determine the 35 effective movement of said lever.

40 2. A variable throw device comprising a main gear, a lever and an arm pivoted on the axis of said main gear, a pinion loosely journaled to said lever, another pinion 45 loosely journaled to said arm but having frictional engagement therewith, said two pinions being in constant mesh with said main gear and engageable with each other to variably determine the effective movement of said lever, and a gear meshing with said main gear and having connections for transmitting a variable movement therefrom.

50 3. A variable throw device including a train of independently and loosely mounted toothed members, two of said members continually intermeshing with a third, one of said members being adjustable relatively to the others, and means for moving one of 55 said members idly until all three members become intermeshed for further, unified movement.

60 4. A variable throw device including a train of independently and loosely mounted toothed members, two of said members continually intermeshing and all of said members being capable of intermeshing for unified movement, one of said members being adjustable variably in advance of another 65 of said members that the extent of independ-

ent movement of said other member may be thereby regulated.

5. A variable throw device comprising a gear wheel and pinions meshing therewith, said pinions having idle movement when separate, one of said pinions being variably adjustable as to its position with respect to the other, and means for moving said other pinion into mesh with said adjusted pinion to permit unified movement of said gear 70 and pinions.

6. A variable throw device comprising a gear wheel and pinions meshed therewith, said gear and pinions being separately journaled, and said pinions having idle movement when separate, one of said pinions being variably adjustable as to its position in advance of the idle movement of the other pinion, and means for moving said other pinion into mesh with said adjustable pinion 80 to permit unified movement of said gear and pinions.

7. A variable throw device comprising a gear wheel and pinions meshed therewith, supports for said pinions having the same 90 axis as said gear wheel, said pinions having idle movement when separate, one of said pinions being variably adjustable as to its position in advance of the idle movement of the other pinion, and means for moving said 95 other pinion into mesh with said adjustable pinion to permit unified movement of said gear and pinions.

8. A variable throw device comprising a gear wheel, a shaft therefor, an arm and a 100 lever extending from said shaft, said arm and lever each carrying a pinion in mesh with said gear wheel, said pinions being capable of independent idle movement with respect to each other and said gear wheel, and said 105 arm being variably adjustable with respect to said lever to regulate the degree of movement required of said lever in bringing its pinion into engagement with the pinion on said arm for unified movement of said gear wheel 110 and pinions in the further travel of said lever.

9. In a variable throw device, in combination, a shaft, a gear wheel loosely mounted thereon, a lever fast on said shaft, a pinion carried by said lever in mesh with said gear, an arm loose on said shaft, and a pinion carried by said arm in mesh with said gear wheel said arm being adjustable with its pinion upon said gear wheel variably with 115 relation to the pinion upon said lever, to regulate the degree of idle movement of said lever.

10. A variable throw device including a gear wheel and pinions meshed therewith, 120 said pinions being independently movable, a support for one of said pinions to adjust it variably upon said gear wheel with respect to the other pinion, and an oscillating lever carrying said other pinion to move it inde- 125 130

- pendently into engagement with said adjusted pinion for unified movement of said gear wheel and pinions in the continued travel of said lever.
- 5 11. A variable throw device having three toothed members capable of independent rotation and capable of locking together for unified movement about a single axis, one of said members being variably adjustable to 10 regulate the degree of unitary movement of another of said members.
12. A variable throw device having three toothed members freely rotatable on separate axes capable of locking together for 15 unified movement about a single axis, one of said members being variably adjustable to regulate the degree of unitary movement of another of said members.
13. In a variable throw device, in combination, a shaft, a gear wheel loosely mounted thereon, a pinion meshed with said gear wheel, a lever fast on said shaft and carrying said pinion, said lever capable of oscillating movement over a determined path, 20 an arm loose on said shaft adjustable to variable positions relatively to said lever, and a pinion carried by said arm in mesh with said wheel, said pinions when engaged by movement of said lever toward the adjusted 25 position of said arm permitting further travel of said lever to move said pinions and gear wheel unitedly.
14. A variable throw device comprising a gear wheel and pinions meshing therewith, said pinions having idle movement when separate, one of said pinions being variably adjustable as to its position with respect to the other, a lever supporting and moving said other pinion into mesh with said adjusted pinion, to permit unified movement of said 35 gear and pinions, and means for retracting said gear wheel upon return of said lever.
15. A variable throw device comprising a gear wheel having means to rotate idly in one direction, and pinions meshing with 40 said gear, said pinions having idle movement when separate, one of said pinions being variably adjustable as to its position with respect to the other, and means for moving said other pinion into mesh with 45 said adjusted pinion, to permit unified movement of said gear and pinions in the other direction.
- In testimony whereof I affix my signature in presence of two witnesses.
